F. SCHROTER

APPARATUS FOR OBTAINING A CONSTANT VOLTAGE

Filed March 16, 1921

Fritz Schröter Inventor

Emery, Varney, Blair & Hoguet*

UNITED STATES PATENT OFFICE.

FRITZ SCHRÖTER, OF BERLIN, GERMANY, ASSIGNOR TO SAFETY CAR HEATING & LIGHTING COMPANY, A CORPORATION OF NEW JERSEY.

APPARATUS FOR OBTAINING A CONSTANT VOLTAGE.

Application filed March 16, 1921. Serial No. 452,824.

To all whom it may concern:

Be it known that I, FRITZ SCHRÖTER, a citizen of the German Republic, and a resident of Berlin, Germany, have invented an improvement in Apparatus for Obtaining a Constant Voltage (for which I have filed an application in Germany Nov. 10, 1917, Patent No. 323,799), of which the following is a specification.

10 This invention relates generally to means for obtaining a constant voltage from an electric circuit subject to voltage or current fluctuations and more particularly to a gaseous conduction device for obtaining a constant voltage.

One of the objects of this invention is to provide a simple, compact and effective device for obtaining a constant voltage or fractional voltage from a circuit whose voltage is subject to fluctuations or the current flow of which is subject to material variations.

Another object of this invention is to provide a gaseous discharge tube of such characteristics that will permit it to function to maintain a substantially constant voltage at its terminals irrespective of material variations in current flowing therethrough.

Other objects will be in part obvious or in part pointed out hereinafter.

The invention accordingly consists in the features of construction, combinations of elements and arrangement of parts, as will be exemplified in the structure hereinafter described and shown in the accompanying drawing, and the scope of the application of which will be indicated in the following claims:

In the drawing the single figure represents diagrammatically a preferred embodiment of this invention.

In the drawing the conductors 10 and 11 represent an electric circuit, the potential of which is subject to fluctuations and from which it is desired to obtain a substantially constant voltage which may be a substantial fraction of the total voltage of the circuit 10 and 11. Across the circuit 10 and 11 there is connected through a suitable current limiting resistance 12 a gaseous discharge tube comprising a vessel or container 13 of suitable material, which may be glass, for example, and the electrodes 14 and 15 mounted therein and connected respectively to the conductor 10 and resistance 12.

The vessel 13 contains a rarefied atmosphere of a gas of the helium group or of a mixture of several gases of this group within which the electrodes 14 and 15 are adapted to operate and maintain a gaseous discharge therebetween. The electrode 15, forming preferably the anode, may take the form, for example, of a cylindrical member either solid or in sheet form, of relatively small cross section and positioned centrally within the substantially cylindrical vessel 13. The cathode 14 may conveniently be made to take the form of a hollow cylinder substantially surrounding the anode 15, the anode 15 and the cathode 14 being provided with suitable conductors to connect them electrically to suitable terminals 17 and 16 respectively exterior of the vessel 13.

The electrodes 14 and 15 may be made of any suitable metal or alloy but the cathode 14 is preferably made of a metal having a relatively small cathode drop in potential. Metals of the alkali group, for example, are characterized by a relatively low drop in potential when employed particularly as cathodes in gaseous discharge tubes of this type and electrodes 14 and 15 may conveniently be made of metals of this group or of alloys containing metals of the alkali group. When the material of the electrodes is chosen as above mentioned and when the gaseous content of the vessel 13 is chosen to be of a gas of the helium group or mixtures thereof, the discharge tube may be given a voltage-current characteristic which will have a substantial portion thereof substantially parallel to the current axis, having due regard for the pressure of the gas within the tube and for the size and arrangement of the electrodes. The portion of the characteristic selected for operation in the embodiment of this invention is that portion of the voltage-current characteristic in which substantial changes in current through the tube result in substantially no changes in voltage across the terminals or result in such changes as are substantially immaterial in magnitude.

The electrodes, if composed of metals of the alkali group or of alloys thereof, readily undergo sufficient ionization upon the initial application of the circuit voltage thereto so that the gaseous discharge between the electrodes is automatically initiated. When gases of the helium group are employed at

2
preferably relatively low pressures, a voltage-current characteristic of the above-mentioned character is obtained and the portion corresponding to relatively small 5 or substantially no changes in voltage for material changes in current therethrough results from the generation of ions or current carriers from the molecules of the gaseous content by collision of the ions already 10 in existence with the molecules of the gas. Hence, the added number of ions in the gaseous content necessary to carry the added or increased current due to an increase in the voltage of the main circuit represented by 15 the conductors 10 and 11 are obtained by collision, as hereinbefore described, without necessitating an increase in the potential across the electrodes otherwise requisite to generate additional ions, the added current 20 being carried by additional ions generated by the collision of the molecules of the gas with the ions already traveling at a high velocity from one electrode to another. This action while difficult of exact analysis, may 25 be substantially that which takes place during that part of the characteristic of the discharge tube at which the latter is operated in carrying out the objects of this invention.

In the embodiment of this invention as 30 illustratively shown in the drawing, a substantial change in voltage across the conductors 10 and 11 forming the electric circuit will cause a substantially proportional change in current through the tube 13 and 35 through the resistance 12 in series therewith. Since, however, the tube has a voltage-current characteristic of the character 40 above described and since the tube operates upon a selected portion of the characteristic as above pointed out, substantial changes in current through the tube 13 resulting from the changes in voltage between the conductors 10 and 11 will cause substantially no change in potential across the 45 terminals 16 and 17 of the tube 13, the characteristic curve of the tube being substantially parallel to the current axis. Hence 50 circuits in which the voltage is desired to be maintained constant may be connected to the terminals 16 and 17 of the discharge tube and may thus be derived from a circuit such as 10 and 11 in which the voltage is 55 subject to substantially wide variations.

It may also be noted that the conductors 55 10 and 11 may constitute part of a series circuit in which the current may vary materially, and that a substantially constant voltage at terminals 16-17 may be derived from such a circuit subject to material current fluctuations.

It will be understood that the resistance 12 in series with the discharge tube 13 functions to limit the current passing through the tube 13 and permits the application of 60 full circuit voltage directly to the elec-

trodes 14 and 15 to insure the automatic starting of the discharge between electrodes and thereafter functions as a protective resistance to the tube 13.

In order to obtain a smaller constant 70 voltage than is maintained at the terminals 16 and 17 of the discharge tube 13, a suitable relatively high resistance 18 is connected across the terminals 16 and 17 and is provided with variable taps, 19-20, from 75 which any desired fraction of the voltage across the terminals 16 and 17 may be obtained.

It will be noted that there has been provided in this invention a simple and effective means for obtaining a substantially constant voltage from a circuit whose voltage or current may be subject to material variations and that the several objects hereinbefore pointed out, as well as others, have 85 been attained.

As many possible embodiments may be made of the above invention and as various changes might be made in the embodiment above set forth, it is to be understood that 90 all matter as hereinbefore set forth is to be interpreted as illustrative and not in a limiting sense.

I claim as my invention:

1. In a device for obtaining a constant 95 voltage, in combination, a main electric circuit subject to variations in voltage, and means connected to said circuit responsive to current changes due to said voltage fluctuations in said circuit, said means containing an electronic conduction path having the inherent characteristic of becoming conductive upon the application of the circuit voltage thereto and adapted to maintain a substantially constant voltage across the terminals thereof through said current changes.

2. In a device for obtaining a constant voltage, in combination, a main electric circuit subject to variations in voltage, means 110 connected in said circuit responsive to current changes due to said voltage fluctuations in said main circuit, said means containing a gaseous conduction path having the inherent characteristic of becoming conductive 115 upon the application of the circuit voltage thereto and including at least one gas of the helium group whereby an increase in the current therethrough is facilitated by the generation of ions by collision without an increase in the potential across said means, and a resistance element connected in series with said means for absorbing the increase in voltage across said means and said resistance element.

3. In a device for obtaining a constant voltage, in combination, a main electric circuit subject to variations in current and comprising a resistance element and a gaseous conduction device in series with one an-

other, said device containing a gaseous atmosphere having the inherent characteristic of becoming conductive upon the application of the circuit voltage thereto and including at least one gas of the helium group whereby the passage of an increased current therethrough is facilitated by the generation of ions by collision of gaseous molecules with ions already in existence, without causing a rise in the potential across said device, and said resistance element functioning to hold the current within a predetermined maximum.

4. In a device for obtaining a constant voltage, in combination, a main electric circuit subject to variations in current and including a gaseous conduction device having an atmosphere containing at least one gas of the helium group, said device being adapted to maintain a substantially constant voltage at its terminals and facilitating the passage of increases in current therethrough by increases in the electronic content by collision of ions already in existence with molecules of the gas without increasing the potential difference at the terminals thereof, said device having the inherent characteristic of becoming conductive upon the application thereto of the circuit voltage.

5. In a device for obtaining a constant voltage, in combination, a main electric circuit subject to variations in voltage, means connected to said circuit responsive to current changes due to said voltage fluctuations in said main circuit, and a resistance element connected in series with said means, said means having a gaseous conduction path composed of at least one gas of the helium group and having the inherent char-

acteristic of becoming conductive upon the application thereto of the voltage of said main electric circuit, the electronic content thereof being adapted to be increased by collision of the molecules thereof with ions already existent in the path to facilitate the passage of increases in current therethrough without increasing the potential drop across said means, and said resistance element being adapted to absorb increases in potential across said main circuit.

6. In a device for obtaining a constant voltage, in combination, a main electric circuit subject to variations in voltage, means connected to said circuit having a gaseous conduction path including at least one gas of the helium group and having the inherent characteristic of becoming conductive upon the application thereto of the voltage of said main electric circuit and adapted to facilitate the passage of an increased current therethrough by increasing the number of electrons therein by collision of the molecules of said gas with ions already in existence therein and without increasing the potential drop across said device, a resistance element connected in series with said means and adapted to absorb increases in the varying voltage of said main circuit, a relatively high resistance connected in parallel with said means adapted to be subjected by said means to a substantially constant IR drop, and means adjustably connected to said relatively high resistance adapted to select therefrom fractional portion of said substantially constant IR drop.

In testimony whereof, I have signed my name to this specification this 22nd day of January, 1921.

FRITZ SCHRÖTER.
